Patented Aug. 23, 1910.

UNITED STATES PATENT OFFICE.

CLAUDE C. INMAN, OF GRAND JUNCTION, COLORADO.

SEPARATOR.

968,242.

Specification of Letters Patent. Patented Aug. 23, 1910.

Application filed January 3, 1910. Serial No. 536,095.

To all whom it may concern:

Be it known that I, CLAUDE C. INMAN, citizen of the United States, residing at Grand Junction, in the county of Mesa and 5 State of Colorado, have invented new and useful Improvements in Separators, of which the following is a specification.

This invention relates to separators and segregating apparatus designed for use in 10 mining, and particularly for the recovering and saving of fine gold, platinum and other precious metals and metalliferous values.

It is the object of this invention to provide a separator which is especially adapted 15 for use in placer mines, and which can be applied to any sluice, dredge, mill, or the like, and by which apparatus the current flow can be regulated to suit the character of the material handled; and also by which 20 apparatus a great economy in the use of water may be effected.

A further object is to provide a separator by means of which the fine gold and other metals usually carried away and lost in 25 placer mining may be saved and accumulated in fine sands or slimes for further treatment by any suitable amalgamating or concentrating process.

The invention consists of the parts and 30 the construction and combination of parts as hereinafter more fully described and claimed, having reference to the accompanying drawings, in which—

Figure 1 is a sectional elevation of the invention on the line X—X, Fig. 2. Fig. 3 is a plan view. Fig. 4 is an end elevation of the lower portion of the machine.

In the common method of using an ordinary sluice, as is usually practiced in placer 40 mining at the present time, the volume of water necessary to carry coarse gravel and boulders along the sluice is sufficient to also carry away the fine gold and other minerals, and thus entails a loss which in many instances renders the operations unprofitable.

To obviate this undesirable result, and to accomplish certain desirable objects herein-after apparent, I employ the device herein-after described, the use of which permits of 50 the volume of water or sluice head being reduced from twenty to forty per cent., and allows the gold or other metals to settle to the bottom of the machine, from whence it

is drawn off on tables or other arrangements for further treatment.

In the drawings, A is the main flume from 5 a mine, through which the volume of water, together with boulders, gravel and concentrates, flows and discharges into an inclined stationary sluice section 2, the bottom of 10 which is provided with screen bars 3 which may be disposed over a portion of or the entire length of the sluice. The sluice section 2 terminates at its outer end in a downwardly inclined discharge portion 4, the incline of which is approximately forty-five degrees and greater than the incline of the 15 section 2.

The bottom of the sluice section 4 is provided with screen bars at 5 for two feet, 20 more or less; the remainder, or lower portion, of the bottom being formed of a slide-able plate 6 mounted in suitable guides on the sluice 4 and adapted to be moved back and forth, or lengthwise up and down, by 25 means of a pinion 7 engaging with a toothed rack 8 on the back of the plate, as will be later described, the lower end of the sluice 4 terminating slightly above the bottom of 30 a chute 9.

Suspended beneath and adapted to telescope the stationary sluice section 2 is a vertically adjustable sluice-box 10 which is hingedly mounted at 10' at its upper end near the juncture of the sluice section 2 with 35 the main flume A. This sluice-box 10 is supported at any convenient point throughout its length by means of chains or cables 11 which are adapted to be wound around drums 12 mounted on a shaft 13 rotatable 40 through a sprocket 14 and chain 14', or in any other suitable manner, so as to raise and lower the outer or lowermost end of the sluice-box 10 in relation to its hinged connection 10'. This is for the purpose of 45 regulating the flow of water so that the same can be made to carry coarse gravel and rocks of any size down to the 5-foot inclined sluice 4 which sits at an angle of about 45°, and through which all the balance of water 50 passes; and owing to the steep incline, rocks and gravel will not stop, even without water. The screen bars regulate the size of the gravel desired to be worked, depending upon 55 the fineness of gold, etc.

A second adjustable sluice-box 15 is dis-

posed beneath the sluice-box 10, and is adapted to receive the materials discharged from the latter. This adjustable sluice 15 is hinged at 16 to the under side of the inclined stationary sluice 4 at a point proximate to the lower termination of the screen bars 5. The opposite end of the adjustable sluice 15 is supported in a similar manner as sluice 2; cables or chains 17 being secured to the sides of the sluice and windable upon drums 17' on a shaft 18 adapted to be rotated by a sprocket 19 and chain 19', or in any other desired manner, so as to adjust the incline of the bottom of the sluice 15. This box 15 is made adjustable for the purpose of regulating the location of fall of water into the separator, and when raised to a point as indicated by dotted lines, shuts off all water and sand from separator, and 20 forces the same down the main sluice 9. This is only done in case of accidents and upon rare clean-ups.

A receiving or separating tank 20 is disposed beneath the sluice 15, into which the 25 flow of materials in the latter may be discharged, the separating tank extending forward beneath the sluice 4 and to some extent under the chute 9. The bottom or floor 21 of the separating tank 20 is inclined forward, as shown in Fig. 1, and leads to an 30 opening 22 in the end of the tank, which is closable by means of a gate 23 which is raised and lowered by suitable means, as a pinion 24 acting on a rack 25 formed on the 35 gate 23. The gated opening 22 connects the interior of the tank 20 with a flume 26 leading to any suitable saving plant, concentrators, or the like, not shown.

A fixed inclined partition 27 is disposed 40 across the interior of the tank 20 at a point near its center, the top of the partition 27 terminating below the top edge of the tank, and the lower edge a short distance above the inclined bottom 21 of the tank. The 45 space 21' intervening between the bottom of the tank and the lower edge of the partition is adapted to be closed by a slidable gate 28 mounted in suitable guides and operated by a rack 29 and pinion 29', so as to open and 50 close the space 21'.

A vertical partition or baffle 30 extends 55 across the tank 20 at a point about midway between the upper end of the inclined partition 27 and the end of the tank and a short 60 distance in front of the open end of the chute 9, through which latter overflow from tank 20 takes place. The upper edge of the partition 30 is on a level with the top of the tank 20 and the lower edge terminates a distance above the bottom 21 of the tank, so as 65 to form an open space 31.

Outlets 32 of any desired number lead 70 from the tank 20 and are disposed at suitable intervals along the bottom or sides of the tank and lead to a slime pipe 33 ex-

tending along the outside of the tank and leading to the concentrators, not shown. Suitable cut-off valves 34 are interposed in the outlets 32, so as to shut off or regulate the flow of slimes through the outlets.

In operation, the water, sand, gravel, boulders and other materials carried by the main flume A are discharged into the screened sluice 2, the sand and fine materials settling through the screen bars 3 onto the 75 bottom of the adjustable sluice 10, while the coarse gravel and boulders remain on top of the screens to be carried forward by the current of water, and are delivered over the screen bars 5 and plate 6 in the inclined 80 sluice 4 into the flume 9, from whence they are removed in any suitable manner. The depth of water in the sluice 2 is regulated by raising or lowering the adjustable sluice 10 by means of the chains 11; ordinarily 85 the outer end of the sluice is set a sufficient distance beneath the sluice, that the surface of the water therein will impel the boulders and gravel into the sluice 4. The sands and fines are carried by the water along the 90 lower adjustable sluice 15 and are emptied into the settling or separating tank 20. The heavier sands and materials settle at once to the bottom of the tank 20 forward of the inclined partition 27, from whence they 95 are drawn off through the opening 22 and conveyed to the concentrators through the flume 26. The finer particles, held in suspension in the water, are carried over the top of the inclined partition 27 by the flow 100 of water, which takes the course indicated by the arrows, Fig. 1; that is, over the partition 27, and under the partition 30; these finer particles settling to the inclined bottom 21 of the tank 20 to be removed through 105 the outlets 32 in the form of slimes, while the clear water overflows into the flume 9. By raising the flume 10 so that its bottom 110 will contact the under side of the sluice 2, and raising the lower sluice 15 to or above the position shown in dotted lines, Fig. 1, by 115 means of the chain 17, the flow of all the water may be directed through the sluice 4 into the flume 9, in which event the plate 6 is moved to its lowermost position, thereby effectively causing the water to flow from the flume A through the sluices 2-4 direct to the flume 9, thus permitting of emptying the settling tank 20 to clean up or repair same; the plate 6 when contacting with the 120 bottom of sluice 9 acting to cut off back flow from sluice 9 into the tank.

By this apparatus the water can be held in complete control at all times and allowed to pass out in sufficient quantity to remove 125 the sands and precious metal, and allow them to settle without the danger of washing them away.

The separator may be made in three sizes, capacities from 250 to 1000 yards of gravel 130

per day. The separator is made open at the top, and of sheet metal, and being usually six feet wide, and sluice but three feet, gives plenty of room for the operator to get into

5 the machine at any time for repairing same. The separator can be installed on any placer sluice, or installed on any dredge without material change to the original plant.

Having thus described my invention, what 10 I claim and desire to secure by Letters Patent, is:

1. The combination with a screen sluice box, of an outside sluice section fitting the same and telescoping therewith, the upper

15 end of the sluice section hinged beneath the sluice box and receiving the discharge therefrom, the lower end of the outside sluice section having a discharge separate from the sluice-box, means for raising and lowering

20 the free end of said outside sluice section, a vertically adjustable hinged sluice box into which said hinged section normally dis- charges, means by which the said hinged

25 sluice box may be made to discharge back into the first mentioned sluice box, and a settling tank into which the said hinged sluice box discharges separate from the first men- tioned sluice box.

2. The combination of a stationary screen 30 sluice box, an inclined continuation thereof also having a screen portion and a sliding plate, a chute into which said inclined portion discharges, a sluice section hinged to the

35 underside of the sluice box and receiving the discharge from the first mentioned screen portion, the free end of said sluice section having normally a discharge separate from the sluice box.

3. The combination of a stationary screen sluice box, an inclined continuation thereof 40 also having a screen portion and a sliding bottom plate, a chute into which said inclined portion discharges, a sluice section hinged to the underside of the sluice box and receiving the discharge from the first mentioned screen portion, the free end of said sluice section having normally a discharge 45 separate from the sluice box, a hinged sluice box into which said hinged section dis- charges, and means for raising and lowering said hinged sluice box to cause it to dis- charge into said chute.

4. The combination of a stationary screen sluice box, an inclined continuation thereof 50 also having a screen portion and a sliding bottom plate, a chute into which said inclined portion discharges, a sluice section hinged to the underside of the sluice box and receiving the discharge from the first men- 55 tioned screen portion, the free end of said sluice section having normally a discharge separate from the sluice box, and a hinged sluice box receiving the discharge from the said hinged section, a settling tank into 60 which said sluice-box discharges, baffles ar- ranged in the settling tank, said settling tank having an overflow discharging into 65 said chute.

In testimony whereof I have hereunto set my hand in the presence of two subscribing 70 witnesses.

CLAUDE C. INMAN.
